CLAIM

The ornamental design for a baby boat with canopy, as shown and described.

DESCRIPTION

FIG. 1 is a perspective view of a baby boat with canopy in accordance with my new design.

FIG. 2 is an elevational view of the front side of the baby boat with canopy of FIG. 1.

FIG. 3. is an elevational view of the right side of the baby boat with canopy of FIG. 1.

FIG. 4. is an elevational view of the rear of the baby boat with canopy of FIG. 1.

FIG. 5 is an elevational view of the left side of the baby boat with canopy of FIG. 1.

FIG. 6 is a top plan view of the baby boat with canopy of FIG. 1; and,

FIG. 7 is a bottom plan view of the baby boat with canopy of FIG. 1.

The evenly broken lines showing a baby are included for the purpose of illustrating environmental structure and forms no part of the claimed design. All other evenly broken lines show portions of the baby boat with canopy that form no part of the claimed design.
